GARMENT HANGER

George H. Bugenhagen, Minot, N. Dak.

Application January 26, 1950, Serial No. 140,663

2 Claims. (Cl. 223—91)

1

The invention relates to a garment hanger and more particularly to the type of garment hanger wherein closable jaws grip and hold the garment positively during storage of the desired article of clothing.

An object of the invention is to provide a garment hanger having closable gripping bars which are susceptible of ready manipulation to close and hold, or open and release a garment.

Another object of the invention is to provide a garment hanger with very positive locking and releasing means.

Still another object is to provide a locking type garment hanger of simple design adaptable to mass production methods from readily available materials.

Another object of the invention is to provide a combination coat hanger and locking type trouser hanger.

Other objects and advantages of the invention will be apparent during the course of the following description taken in connection with the annexed drawings wherein:

Fig. 1 is a side elevation of the garment hanger of the invention in full lines showing however the position some of the elements occupy at various times in dotted lines.

Fig. 2 is a section view along lines 2—2 of Fig. 1 viewed in the direction of the arrows showing the jaws of the hanger in a closed position.

Fig. 3 is sectional view along lines 3—3 of Fig. 1 showing the position assumed by the various elements when the jaws are in an open position.

Fig. 4 is a fragmentary sectional view along lines 4—4 of Fig. 1 showing the means for locking the jaws into engagement with the garment.

Referring to Fig. 1 garment gripping bar 1 is opposed by a second bar 2 (not shown in Fig. 1). Paired supporting legs 3 and 4 are suitably attached to bar 1 in spaced apart relation. Both legs are formed into closed coiled loops 5 and 6 through which cross rod 7 extends. Cross rod 7 may be extended at either end into coat hanging arms 8 and 9 if desired or these elements may be omitted and cross rod 7 riveted or flared at either end after clearing loops 5 and 6. The legs 3 and 4 extend a short distance above cross rod 7 and at a different angle (see Fig. 2) as seen at 10 and 11 after which they bend sharply to form converging arms 12 and 13 which are integral with each other at their apex 14. Arms 12 and 13 extend at a different angle than the remainder of the legs 3 and 4 when viewed either from the side or the end (see Fig. 2). Gripping bar 2 is similarly engaged by supporting legs 15 and 16

which are formed at their upper end into a structure of very similar appearance to that just described excepting that as viewed from the side the second structure gives the appearance of being framed inside of the first structure. Both legs 15 and 16 are formed into closed coiled loops 17 and 18 through which cross rod 7 extends. Legs 15 and 16 extend a short distance above cross rod 7 as seen at 19 and 20 and at a different angle than formerly (see Fig. 2) after which they bend sharply into converging arms 21 and 22 which are integral with each other at their point of meeting 23, arms 21 and 22 extend at a different angle from the remainder of legs 15 and 16 when viewed from either the side or the end. A clip member 24 is centrally positioned on cross rod 7 and serves as a support for the leg 25 of hanger hook 26 pivotally mounted on pin 27 passing through clip 24. The leg 25 of hook 26 passes between the apex formed by the two sets of arms 12 and 13, and 21 and 22. Spring member 28 is mounted on cross rod 7 and is provided with L-shaped ends 29 and 30 which engage legs 4 and 15 for urging the same outwardly when the gripping bars are unlocked and provide for more ready reception of the garment.

In Fig. 2 the relation of the various elements, with the hanger in a closed position, is shown in clearer detail. For example legs 4 and 16 supporting gripping bars 1 and 2 extend upwardly in slightly converging relation until they are formed into loops 6 and 18. Thereafter above the loops 6 and 18 the legs 11 and 20 diverge rather sharply for a short distance and then bend sharply inward into arms 13 and 22 and meet leg 25 of the hanger hook 26 at 14 and 23.

In Fig. 3 the relation of the various elements is shown with the gripping bars 1 and 2 in the open position. In this view the hanger hook 26 and its supporting leg 25 has been pivoted forward which in turn has allowed the gripping bars 1 and 2 to separate by virtue of the frame formed by converging arms 12 and 13, sliding over the frame formed by converging arms 21 and 22. The spring 28 acts to urge the jaws apart when the hanger leg 25 is pushed forward or backward out of engagement with the point of convergence of arms 12 and 13, at 14, and arms 21 and 22 at 23.

In Fig. 4 the contour of converging arms 12 and 13 is seen to provide a shallow recess or indent at 14. The recess or indent at 14 serves to securely hold hanger hook leg 25 in a vertical position when the leg 25 is brought into engagement with the recess or indent, yet allows the leg to be directed forward or backward upon application of

slight pressure. The contour of converging arms 21 and 22 is shown as a flat portion at 23 at a point opposite the indent at 14. Although points 14 and 23 are not quite opposite, 14 engaging leg 25 slightly higher than 23, the displacement is so slight as to cause no undue bending stress on leg 25. It will be evident that spring member 28 is a refinement of the device which may be omitted without departing from the spirit of the invention.

The operation of the hanger will be best understood from the following description in connection with the placement of a garment therein. With the hanger in an open position such as is shown in Fig. 3 trouser cuffs or the like may be placed between the gripping bars 1 and 2 and the hook 26 and leg 25 raised toward the vertical position. The leg 25 will encounter arms 12 and 22 or 13 and 21 and as it moves upwardly the arms will be wedged apart until the hook leg 25 engages the indent at 14 and the level portion at 23. At this point gripping bars 1 and 2 will have been urged strongly together to hold the trouser cuffs securely. To release the trousers it is only necessary to move leg 25 out of the indent and spring 28 will force the gripping bars apart to release the garment.

It will be apparent that if desired the coat hanging arms 8 and 9 may be readily omitted in case only a trouser hanger or a device with gripping bars only is desired. In this case cross rod 7 will only need to be riveted or burred over so as to retain engagement with loops 5 and 6. It will be readily appreciated that the gripping bars may be made of wood, plastic, or the like while substantially all of the remainder of the structure may be formed from suitable gage wire to provide simple and rapid assembly.

I claim:

1. In a garment hanger the combination which includes a pair of garment gripping bars, a pair of supporting rods for each gripping bar, said rods being formed into loop portions spaced from the gripping bars with the holes in the loops being in alignment, a cross member extending through the loop portions to allow swinging movement of the gripping bars, a hook member including a shank portion mounted at the shank end for partial rotational movement on the cross member, and means for holding the gripping bars in gripping engagement consisting of extensions of the rod

members formed beyond the loop portions into modified opposed V-shaped bars with their apexes adapted to closely approach each other and their legs diverging from each other when the gripping bars are in a closed position and with one of said V-shaped bars being adapted to move over the other as the gripping bars move apart, said V-shaped bars being formed adjacent their upper ends into a flat section and an indented section respectively so as to receive the hook shank in locking engagement, said V-shaped bars also being adapted to be wedged apart as the shank of the hanger hook is moved to the vertical position.

2. In a garment hanger the combination which includes a pair of garment gripping bars, a pair of supporting rods for each gripping bar, said rods being formed into loop portions spaced from the gripping bars with the holes in the loops being in alignment, a cross rod extending through the holes in the loops and being formed at each end into a coat hanging arm, a hook member including a shank portion mounted for partial rotational movement on the cross rod, a spring carried by the cross rod associated with each set of supporting rods adapted to urge them apart, and means for holding the gripping bars in gripping engagement comprising extensions of the rod members formed beyond the loop portions into modified opposed V-shaped bars with their apexes adapted to closely approach each other and with their legs diverging from each other when the gripping bars are in a closed position and with one of said V-shaped bars being adapted to move over the other as the gripping bars move apart, said V-shaped bars being formed adjacent their upper ends into a flat portion and an indented section respectively so as to receive the hook shank in locking engagement, said V-shaped bars also being adapted to be wedged apart as the shank of the hook is urged to the vertical position.

GEORGE H. BUGENHAGEN.
